Patented Dec. 6, 1921.

Fig. 1

UNITED STATES PATENT OFFICE.

MORRIS M. SCHRAGO, OF LOS ANGELES, CALIFORNIA.

SEWING-MACHINE.

1,399,086.

Specification of Letters Patent.

Patented Dec. 6, 1921.

Application filed April 5, 1919. Serial No. 287,683.

To all whom it may concern:

Be it known that I, MORRIS M. SCHRAGO, a citizen of the United States, residing at Los Angeles, in the county of Los Angeles 5 and State of California, have invented new and useful Improvements in Sewing-Machines, of which the following is a specification.

This invention relates to improvements in 10 sewing machines, and more particularly to the seaming together of materials where fullness is necessary on the top seam.

It has for its object to provide a new and simple and effective means whereby the 15 seaming up of any garment, belting, leather, rubber, canvas, goods, as well as other miscellaneous materials where fullness on the top seam is required.

In practising my invention I provide a 20 presser foot and a ribbon or strip, one side of said ribbon or strip having spaced serrations thereon. This strip has its smooth face adjacent to the under side of the presser foot and the width of said strip is usually 25 equal to the width of the presser foot toe.

If it is desired to seam any garment in which fullness is necessary on the top seam, the garment is placed on the sewing machine in the usual position necessary for sewing 30 and the strip is extended so as to lie upon the garment, after which the presser foot is released by lever means into operative position. The serrated surface of the strip then bears on the top surface of the material. In 35 this case by pushing said material toward the presser foot the top cloth would become corrugated or have a full appearance, while the undercloth to which the top cloth is to be sewed would remain flat. It will be understood 40 that as the needle mechanism commences its work the stitches will follow along the edge of said strip, and the presser foot and the strip as well as the feed dog underneath the garment will feed the garment along keeping the under cloth straight 45 while the top cloth is seamed in in its fullness. The serrated surface of the strip readily prevents the goods undergoing the sewing process from slipping. The ordinary 50 method of obtaining fullness in garments such as sleeve heads, the bottom of ladies' dresses, as well as other garments, is to first in the case of sleeve heads to baste in said sleeves with the sleeve head having 55 fullness in relation to the cloth in which said

sleeve head is basted. The garment is then seamed and pressed until the fullness is removed so that the goods lie as straight as the piece to which it was basted. When this is accomplished the garment is then sewed 60 on a sewing machine. Obviously the presser foot coöoperating with the feed dog underneath said presser foot stretches the garment straight. The invention permits the sleeve head to be sewed in straight. 65

However, my invention overcomes all this unnecessary labor, saving time and thread. With my invention it is possible to seam up any garment where fullness is necessary on the top seam directly on the sewing machine 70 without any basting, seaming, etc.

In addition it is most difficult for any but the most expert manipulator of sewing machines to sew a perfectly straight seam especially in sleeve heads or around the bottom 75 of ladies' dresses, as above-mentioned, but with my invention it is perfectly possible to overcome this difficulty and sew a straight seam, inasmuch as the edge of the strip acts as a guide for the operator as well as holding the goods in place when said goods is resting on the top frame of the sewing machine. By using my invention the most inexperienced person may after a few weeks 80 practice become more expert than would an 85 all-around operator with years of experience be able to accomplish, by the old method of obtaining fullness on the top seam.

With the above and other objects in view, my invention consists in novel and useful 90 provision, formation, construction, combination, association and inter-relation of parts, members and features, all as disclosed in the accompanying drawing, described in the specification and finally defined in claims. 95

In the drawing:

Figure 1 is an end view of a sewing machine head with my improvement connected thereto;

Fig. 2 is a fragmentary isometric view of 100 my improved sewing machine member showing a presser foot with container member for holding a strip as well as means joining said container and presser foot;

Fig. 3 is a cross sectional view of the 105 container member;

Fig. 4 is an isometric view of the presser foot and means joining said presser foot and container member, said means being shown as fragmentary; 110

Fig. 5 is a fragmentary isometric view showing the serrated surface of the strip; and

Fig. 6 is a side view of the strip showing the serrations thereon.

Corresponding parts in all the figures are designated by the same reference characters.

Referring with particularity to the drawing, A designates a sewing machine head 10 with its usual attendant features as a presser bar 1, a needle bar 2, presser foot thumb screw 3, and needle 4. B designates the bed of a sewing machine with a feed dog 5 projecting therethrough. C designates my improved means comprising a presser foot *a*, a strip *b*, a container member or casing *c* for holding the strip or ribbon *b* and a member *d* joining said container member *c* and the presser foot *a*. The presser foot *a* corresponds in design to any presser foot used on and made for any make of sewing machines. The presser foot *a* is attached to the presser bar 1 by the presser foot thumb screw 3 in the usual manner. The member *d* is fastened to the presser foot *a* as at 6 and forms an integral part with said presser foot *a*. In the showing the presser foot *a* and the member *d* have a web member 7 between them to maintain rigidity.

30 The member *d* is channeled as at 8, said member *d* having a plane upper surface 9, sides 10 and 11 and spaced bottom members 12 and 13 parallel with said top member. By referring to Fig. 4 it will be observed 35 that the channeled portion of the member *d* connecting the presser foot *a* has its side members 12 and 13 in spaced relation to the foot of said presser foot *a* as at *e*. This is in order to allow the strip member *b* to 40 pass from within said channeled portion 8 and down under the toe of the presser foot *a* as illustrated in Fig. 1. The member *d* is connected to the presser foot *a* and is of such a width that the strip *b* is guided at and 45 under the toe 14 of the presser foot *a*, so that the edge of the strip *b* is even with the edge of the presser foot *a* as at 15, that is, the edge next to the needle 4.

The strip *b* is provided at its free end 50 with a clip *f*, and the clip *f* is bent upward at its end as at 17 and is for the express purpose of hooking to the bent up portion of the toe of the presser foot member *a* as at 18 and in addition prevents the strip *b* from 55 being drawn into the channeled portion of the member *d*. The opposite end of the member *d* is connected to the member *c* and the member *c* is provided with a slot *x* which joins with the channeled portion 8 of the member *d*. The casing or container member *c* is provided with a partition *g*, which partition *g* divides the casing or container *c* into 60 two parts. One of said parts as *h* holds the strip *b* while the other section *j* holds a 65 spiral spring or tension means *y*. The par-

tition *g* is held to the inner surface of the member *c* in any approved manner. A rod 19 extends through and at a median section of the partition *g*. This rod is provided with collars 20 and 21. The collar 20 is provided with threaded perforations 22 and joins with spaced recesses 23 in the rod 19; thus by inserting a screw in the perforations 22 the collar 20 may be rotated and locked into any position desired for the purposes 70 about to be stated. The collar 21 is likewise either permanently or adjustably connected to the rod 19. The spiral spring *y*, has one end connected by suitable means to the inner surface of the member *c* and on the side 75 designated as *j*, while the opposite end is connected to the collar 20. The opposite end of the strip, that is, the end that is farthest removed from the clip *f* is connected to the collar 21, and thus when the strip is wound 80 upon the collar 21 the tension with which it is drawn into or out of the container *c* may be regulated by adjusting the collar 20 which connects with the spiral spring. The container *c* is provided with covers or caps *k*. 85 These caps *k* have at their median section as 24, a bearing, said bearing accommodating the ends of the rod 19, and which, in conjunction with the member *g* supports the rod 19 so that same may rotate as the strip 90 *b* is moved inwardly or outwardly of the container *c*. The member *c* is likewise supplied with slots 25, said slots having two right-angled portions. The caps *k* are provided with small pins 26 extending radially 95 downwardly, and it is intended that the pins should engage the slots 25 so that the caps *k* may be locked in place upon the container *c*.

While I have hereinbefore specifically described my invention and its several features with reference to the particular embodiments thereof which are illustrated in the drawing, it will be understood that the invention in principle is equally applicable to any style of machine in which sewing 105 is accomplished; and further, that it may be variously modified in its various details within the scope of the appended claims, without departing from the spirit or sacrificing the advantages thereof.

Having thus disclosed my invention, I claim and desire to secure by Letters Patent:

1. In a sewing machine, the combination with a presser foot, and needle mechanism, of a ribbon adapted to be extended so as to 110 overlie work beneath and beyond the presser foot or be retracted toward the presser foot; means being provided for housing the ribbon when retracted; said means having a tension device tending to retract said ribbon. 115

2. A device of the character described, including a casing, a presser foot, and means uniting said casing and foot; a ribbon confined within said casing and adapted to be 120 extended therefrom beneath and beyond the 125

presser foot and retracted toward the presser foot into the casing.

3. A device of the character described, including a casing, a presser foot, and means uniting said casing and foot; a ribbon confined within said casing and adapted to be extended therefrom beneath and beyond the presser foot and retracted toward the presser foot into the casing moving in conjunction with and responsive to movement of the work; said means being channeled to receive said ribbon and to act as a guide for same.

4. A device of the character described, including a casing, a presser foot, and means uniting said casing and foot; a ribbon confined within said casing and adapted to be extended therefrom beneath and beyond the presser foot and retracted toward the presser foot into the casing; said ribbon having a clip at its free end for engagement with said presser foot to limit the retraction of said strip.

5. A device of the character disclosed, including a presser foot, a casing joined to said presser foot, and a ribbon normally coiled within the casing and adapted to be passed under the presser foot and extended in length beyond the presser foot.

6. A device of the character disclosed, including a presser foot, a casing joined to the rear of said presser foot, and a ribbon normally coiled within the casing and adapted to be passed under the presser foot and extended in length beyond the presser foot; there being means for exerting a tension upon said ribbon to retract the same.

In testimony whereof, I have signed my name to this specification in the presence of two subscribing witnesses.

MORRIS M. SCHRAGO.
